(57) **CLAIM**

The ornamental design for pair of gloves for training and evaluation of football catching, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a pair of gloves for training and evaluation of football catching showing my new design; and,

FIG. 2 is a rear perspective view of one of the gloves shown separately for clarity of illustration thereof.

The characteristic feature of the design resides in a pair of training gloves where the color coordination indicates to an observer the correct position of the hands and whereby the diamond indicates to the person receiving, the correct position of his hands for safety and proper catching purposes.
